(57) **CLAIM**

The ornamental design for a set of air cushions for hovercraft toy vehicles, as shown and described.

DESCRIPTION

FIG. 1 is a perspective view of the set of air cushions for hovercraft toy vehicles showing my new design;

FIG. 2 is a left side view thereof, the right side being a mirror image of the left side;

FIG. 3 is a front view thereof;

FIG. 4 is rear view thereof;

FIG. 5 is a top view thereof; and,

FIG. 6 is a bottom view thereof.

The broken lines are for illustrative purposes only and form no part of the claimed design.
